METHOD OF SENDING IMPULSES FOR AUTOMATIC TELEPHONE EXCHANGES.

Application filed February 4, 1925, Serial No. 6,735, and in Germany September 30, 1924.

This invention relates to a transmitting arrangement for automatic telephone exchanges, more particularly for those of large size, in which the advantages of forming 5 large groups, for instance groups of 400, are particularly important.

As is well known, in automatic exchanges of the latter kind it is possible to employ directly number dials with ten divisions but 10 only by using a so called "register", that is a device for translating the impulses sent out by the dial on a decimal basis to a series of impulses corresponding to the grouping of the terminals on another non-decimal basis. 15 Such devices, which as a rule comprise a number of step switches receiving the current impulses sent out by the subscriber, and other switches transmitting the received impulses, as well as control-switches and relays, 20 are always extraordinarily complicated; they render therefore the installation costly and make it difficult to keep up an automatic exchange.

This invention shows a simple way for attaining the desired object, permitting firstly 25 the use of the usual number dials provided with only ten digits, which at the same time may also contain letters, and further the direct operation of switches with a great subdivision of the contacts, for instance of 30 switches with twenty steps, so as to obtain large groups of exchanges.

This is achieved by a duplication (or multiplication) of the possibility of connection 35 in the direction of the called subscriber but is also further developed in the sense that the increase in the possibility of connection is extended to all (or several) selection steps.

Another feature of the invention consists 40 in the fact that the number (or letter) set in front of the selective number proper, fixes the combination determining whether all (or several) following selection stages or steps 45 belong to one or another group of selective connections.

For carrying out the invention, when using selectors arranged for sending twenty 50 current impulses, these current impulses required for the purpose can be readily divided into two groups of ten. For each of the two groups the digits 1 to 10 can be used,

but they can be differentiated by an added group designation letter A or B.

To enable the capacity of any selection stage to be doubled, care must be taken to 55 enable each selection digit of the connection number to be rendered operative in two ways, for instance, a selected number 5-4-3 can call up the connection for A⁵, A⁴, A³ in one group, or A⁵, B⁴, A³ in another group, or 60 B⁵, A⁴, A³ in yet another group.

According to this kind of subdivision into two group halves A¹ to 10 and B¹ to 10, in one system for, say, three series of current impulses which each control 2 x 10 outgoing 65 connections that is to say comprise 20 x 20 = 8000 lines, it is possible to have the following combinations determining whether the connection called belongs to the group A or group B.

Group halves of the selection stages or steps.

Combination.

1	A A A	70
2	A A B	75
3	A B A	75
4	A B B	75
5	B A A	80
6	B A B	80
7	B B A	80
8	B B B	80

Consequently eight combinations are possible in this case. It will be seen that in systems for four series of current impulses (160,000 lines), there will be obtained sixteen combinations, for five series of current impulses (3,200,000 lines) - 32 combinations, and so on. (On the contrary in system with only two stages of twenty division selectors only four combinations will be obtained.)

The basic idea of the invention is first to fix by a previous selective operation the combination required for the selection of the desired subscriber, and further to construct the first current impulse receiving device in such a manner as to control the subsequent selective operations so that the succeeding current impulse series of the desired kind travel in the one or in the other direction as required.

For carrying out this process various ways can be adopted, all falling within the scope

of the present invention, in as far as they utilize this group system.

The apparatus could be arranged in such a manner that the preceding current impulse sent produces, according to the so called combination number or combination letter, in the single selection stages, such an operation or control by the switches that the devices they advance allow the current impulses for each of these stages to become operative in the group half A or in the other half B. The same continued on two stages, allows the action to take place on 2×2 , that is to say, on the fourfold number of group halves and so on. It is therefore possible, by a previous sending of the combination number, to influence each subsequent current impulse series in such a manner that it shall become operative in one or in the other direction.

In this method of construction, ordinary number dials provided with ten finger holes are used, in which for each number the corresponding number of current interruptions of the loop occurs in the well known manner without the formation of large groups being thereby restricted or the construction of the transmitter complicated. The advantage consists firstly in the use of standard dials, which is also important for traffic with exchanges working on the old system with groups of 100; moreover, a considerable advance is made compared with the large group systems hitherto known. These have been so arranged up to now that either the selection of a number by the subscriber sets a register which then sets the switches in the single selection stages, or for instance one number dial is used for sending out twenty current impulses. In any case when the connection is made, there are considerable losses of time, either at the exchange owing to the subsequent setting of the switches affected by the register, or at the subscriber's station owing to the slower running down of the dials, naturally required in the case of dials with more than ten divisions. These losses of time are also eliminated by the present invention.

In Figure 1, W^I is a switch assumed to be a simple small rotary selector by means of which the desired combination is set. The switch W^I is provided with as many brush arms as there are selection stages, and with as many fixed contacts as there are combinations, the said contacts being either insulated or earthed. For an 8000 system for instance each selector is provided with three brushes and with eight fixed contacts, which case is illustrated in Figure 1. The switch W^{II} which is advanced one step after each series of current impulses, comes consecutively by its arm k into contact with the switch arms k_1, k_2 , etc. and influences the sequence of the number selection, accord-

ing as the switch W^I becomes connected to earth or not. The switch W^{II} is provided with only one brush arm and with a number of fixed contacts, equal to the number of the selection stages.

In Fig. 2 is shown a modification of the system.

The operation is as follows:

As soon as the subscriber takes off his receiver the current relay A in the call finder CF becomes operative through operations which are well known and need not be described here. At the same time, by proper switching operation, the contact x connects the contact a_2 to earth. When the subscriber transmits then the first digit the circuit of magnet D^I through nd^{II}_1, a_2 and x is repeatedly closed. The relay U which is slow to deenergize also becomes then operative and in its turn operates the second retarding relay T. The switch arms of the selector W^I are set by the magnet D^I on a given contact. After the first digit is sent, the relay U releases and closes, through contact u and the working contact t , a circuit for the magnet D^{II} . The latter then becomes operative, and advances the arm k_4 . After the expiration of a certain retardation period, the contact t falls back again and opens the circuit of D^{II} so that its armature drops down. As soon as the switch W^{II} leaves the normal position, the contacts nd^{II}_1 and nd^{II}_2 are operated. The working contact nd^{II}_1 switches off the magnet D^I , so that the selector W^I is no longer influenced by the next following current impulse series, whilst the contact nd^{II}_2 connects the contact a_1 to earth, so that at the next digit current impulses are repeated over the contact a_1 into the a - line.

In order to explain how the succeeding sending of impulses is influenced by the currents sent by the previously set combination, the use of a line selector LS as in Figure 1, is fully set forth, as in the use of such a switch the conditions are more difficult than with the group selectors, since in the line selector action two sets of current impulses become consecutively operative, whilst in the group selectors only one set of current impulses is required. As will be seen from the drawing of the path of current, the b branch of the connection wire to the group or wire selector can be connected through k_4 consecutively to the single arms k_1, k_2 , etc. of the selector W^I , and here be either insulated or connected to earth, according to the combination set. In the single selectors, on the b side, are provided switch relays, which, according as the b branch finds earth or not in the selector W^I , either become operative or remain at rest. In the line selector, as it is a question here of the last two selection stages, there are accordingly provided also two switch relays Q^I and Q^{II} . S^I to

S^V are sequence switch contacts which are closed for the connection of the indicated selection stages controlled thereby.

The portion of the diagram to the right of 5 and under the main diagram is a continuation of the latter at the points a , b . By way of example it will be assumed that the calling up subscriber selects the call number 6543; that means that by the selection 10 of the first digit 6, the following three digits are fixed as B^6 , A^4 and B^3 .

In the example under consideration let it be assumed that, as soon as, by the first selective operation, the selector W^I is set to 15 the desired combination (6), and at the same time the arm k_4 of the selector W^I is advanced to the first contact, the next selection digit (5) has been used for the group selection, (not further described), controlled 20 by the combination arm k_1 . At the same time let it be assumed that the selector W^I with its arm k_4 has arrived in the second position, owing to which a_1 is connected to earth through nd^H_2 , whilst at the same time 25 the switch relay Q^I connected to the b branch, is either rendered operative or remains at rest, according to the combination.

If we consider now the last two selection stages of the line selector in our example, in 30 this case the arm k_2 of the selector W^I would be set, for the penultimate current impulse, on the sixth contact (not earthed). In that way there is no closing of circuit over k_4 and k_2 , and Q^I remains at rest.

35 When now the current impulses of the penultimate digit (4) are sent out, the relay Y is operated through the sequence switch contact S^V in the position 1; this relay Y , by means of its contact y over the sequence 40 switch arm S^{VI} in the position 1, advances the intermediate selector IS . This selector is intended to transfer its record later to the line selector proper. After the termination 45 of the penultimate current impulses, the switch W^I passes over to the third contact so that the arm k_4 when on k_3 is earthed in the case of our example (combination 6). The relay Q^{II} becomes therefore operative over the control switch S^{II} in the position 2 50 and remains locked over the contact q^{II}_5 over S^{IV} etc. to the end of the connection. When the last digit is being sent, the relay Y again becomes operative over the sequence switch S^V and repeats the impulses by its contact 55 y , the current impulses over S^{II}_2 and the a branch, directly to the connector.

As regards the connection of the contacts of the relays Q^I and Q^{II} it is to be understood 60 that the α testing wire (not shown) would be carried correspondingly by the contacts of these relays, so that in the position of rest of both relays, the connection goes to the connectors of the first hundred; if the relay Q^{II} alone becomes operative, connection is 65 made to the second hundred, if the relay

Q^I only becomes operative, to the third hundred, whilst if both relays become operative, the fourth hundred will be reached. In our example, as the combination selected is B A N, the relay Q^I is not operated, but the 70 relay Q^{II} is. Consequently a connector of the second hundred is reached in the selected 400 group.

It will be seen therefrom that with the installation described it is possible, as soon as 75 the combination has been fixed by a previous selection, to select with only two current impulse emissions of a 10 division number dial, any given subscriber out of a 400 group, with three current emissions out of an 8000 group and so on. As the operation of the switch relay takes place each time before the beginning of the current impulse emission, and without any loss of time, the connection is ready immediately after the last current impulse emission. Consequently the losses of 80 time, such as occur in other systems owing to the subsequent setting of the selectors on the "register", are avoided here.

Figure 2 shows a further development of the basic idea. As already stated, for an installation with three current impulse emissions (capacity $20 \times 20 \times 20 = 8000$) eight different three place combinations are required. The installation in such a case would contain, in addition to the line selectors, only one group selector. In the case of an extension of the system, it would be necessary to have one more group selector. This can be avoided in many cases provided that the installation does not exceed a given size, by utilizing, according to Figure 2, the preliminary selection stage for the setting of the combination, at the same time also for the selection of the main groups (exchange 90 groups). Assuming that the switch W^I is provided with 20 contacts, the eight combinations required for 8000 lines can be repeated for the second time on the contacts 95 17-20. (In Figure 2, only the combinations up to 16 are shown.) If, for instance, the preliminary selector (PS) is utilized, then it is possible, by connecting the testing relay P of the selector PS to earth through the arm k_0 , to ensure either that the IV VW preliminary selector will move to the leads to the one or the other 8000 group, according 100 as W^I is set on the first eight or on the second eight contacts. In each group it is possible to have eight combinations worked by first group selectors. It would therefore be possible, by using first group selectors with the first half of an 8000 group employing 20 contacts, to work installations with 105 20,000 lines, which at present must be worked on the 100,000 system and first, second and third group selectors for operation, whereby extraordinary saving can be effected 110 by the use of our invention.

For building large exchanges on this sys- 115 120 125 130 135

tem, for each selection stage for selecting large groups, the whole selection possibility of the dial up to the figure 10 can be utilized and in a corresponding manner the addition 5 of the combinations not yet utilized (for instance from the 8th to the 10th or 16th to 20th group) owing to which group units with four selection stages can be formed. Also for larger networks which go beyond 10 4 selection stages, it will be possible to build the 100,000 unit on our combination system, whilst for the selection of the first stage an ordinary preliminary selection on the decimal system could be advantageously 15 used.

What we claim is:

1. In a telephone exchange system, subscribers' lines, subscribers' sets with dials, automatic switches for establishing connections between said lines, multi-position group selector switches, multiple terminal banks for said switches upon a larger base than the decimal one, each bank of terminals being sub-divided in two groups, a relay 20 for each multi-position switch to operate the one or the other of the said two groups, multi-position connector switches, multiple terminal banks for the connector switches each sub-divided into four groups, a pair of 25 relays for each connector switch for governing the terminal bank thereof, a progressively operating switch with brushes, one for each group selector and two for each connector, a combination of insulated and 30 earthed contacts upon which the brushes are positioned when the first digit is dialed, means to selectively operate the said relays on the impulses from the second to the last digit of the dial, means to adjust the multi- 35 position switches directly by the dialing impulses, and means for variably controlling said multi-position switches for governing one or another of said connector switch bank groups under the control of the relays dependent upon the 40 first progressively operating switch being positioned for connection with insulated or earthed contacts of said combination of insulated and earthed contacts.
2. In a telephone exchange system, subscribers' lines, subscribers' sets with dials, automatic switches for establishing connections between said lines, multi-position group selector switches, a multiple terminal bank 45 for each of said switches upon a larger base than the decimal one, each bank of terminals being subdivided into two groups, a relay for each multi-position switch to operate the one or another of said groups, multi-position 50 connector switches, a multiple terminal bank for each connector switch, each subdivided

into four groups, a pair of relays for each connector switch for governing the terminal bank groups thereof, a progressively operating switch with brushes one for each group selector and two for each connector, a second progressively operating switch to control the sequence of movements of the brushes of the first progressively operating switch, insulated and earthed contacts upon which the brushes are positioned upon the first digit being dialed, means for selectively operating the relays on the impulses from the second to the last digit of the dial, means to adjust the multi-position switches directly by the dialing impulses, and means for variably controlling the multi-position switches for governing one or another of said connector switch bank groups under the control of the said relays dependent upon the first progressively operating switch being positioned for connection with insulated or earthed contacts of said combination of insulated and earthed contacts.

3. In a telephone exchange system, subscribers' lines, subscribers' sets with dials, automatic switches for establishing connections between said lines, multi-position group selector switches, multiple terminal banks for said switches upon a larger base than the decimal, each bank of terminals being sub-divided in two groups, a relay for 55 each multi-position switch to operate the one or the other of the said two groups, multi-position connector switches, multiple terminal banks for the latter switches each sub-divided in four groups, a pair of relays for each connector switch for governing the terminal bank groups thereof, a progressively operating switch with brushes, one for each group selector and two for each connector, a second progressively operating switch to control the sequence of the brushes of the first progressively operating switch, a group of insulated and earthed contacts selectively engaged with the brushes under the first and second digit impulses of the dial, means to selectively operate the relays from the third to the last digit of the dial, means to adjust the multi-position switches directly by the dialing impulses, and means for variably controlling the multi-position switches for governing one or another of said connector switch bank groups under the control of the relays dependent upon the connection of said relays with the insulated and earthed contacts.

In testimony whereof we have affixed our signatures.

KARL HERSEN.
WULF HIRSCHBERG.
